UNITED STATES PATENT OFFICE.

GUSTAV V. HUGO, OF OAKLAND, CALIFORNIA.

DESIGN FOR A SOUVENIR-CARD.

43,820.

Specification for Design.

Patented Apr. 8, 1913.

Application filed November 4, 1912. Serial No. 729,503. Term of patent 3½ years.

To all whom it may concern:

Be it known that I, GUSTAV V. HUGO, a citizen of the United States, residing at Oakland, in the county of Alameda and State of California, have invented a new, original, and ornamental Design for Souvenir-Cards, of which the following is a specification.

The figures of the drawing are elevations of a souvenir card showing my new design.

I claim:

The ornamental design for a souvenir card as shown.

In testimony whereof I affix my signature in presence of two witnesses.

GUSTAV V. HUGO.

Witnesses:

JOHN A. MELIN,
MARGARET MACLEOD.
